(57) **CLAIM**

The ornamental design for a tapered cup, as shown and described.

DESCRIPTION

FIG. 1 is a front perspective view of the tapered cup; FIG. 2 is a front elevation view thereof, the right, left and rear elevation views being substantially the same as the front elevation view;

FIG. 3 is a top plan view thereof;

FIG. 4 is a bottom plan view thereof;

FIG. 5 is a cross-sectional elevation view of the cup of FIG. 1 taken at line 5-5 of FIG. 3;

FIG. 6 is a front perspective view of a tapered cup according to another embodiment;

FIG. 7 is a front elevation view of the tapered cup of FIG. 6, the right, left and rear elevation views being substantially the same as the front elevation view;

FIG. 8 is a top plan view of the tapered cup of FIG. 6; FIG. 9 is a bottom plan view of the tapered cup of FIG. 6; and,

FIG. 10 is a cross-sectional elevation view of the cup of FIG. 6 taken at line 10-10 of FIG. 8.

The portions of the tapered cup shown in broken lines form no part of the claimed design.
